UNITED STATES PATENT OFFICE.

EVERETT R. BURTNELL, OF LOS ANGELES, CALIFORNIA, ASSIGNOR OF ONE-HALF TO
HOMER A. BRUNELL, OF LOS ANGELES, CALIFORNIA.

VALVE MECHANISM FOR INTERNAL-COMBUSTION ENGINES.

Application filed December 22, 1920. Serial No. 432,529.

To all whom it may concern:

Be it known that I, EVERETT R. BURTNELL, a citizen of the United States, residing at Los Angeles, in the county of Los Angeles and State of California, have invented new and useful Improvements in Valve Mechanism for Internal-Combustion Engines, of which the following is a specification.

It is the object of this invention to provide a novel valve mechanism for an internal combustion engine including a piston valve received within a valve chamber and a sleeve valve received upon the outside of the valve chamber in an annular space provided between the latter and an external sleeve.

More specifically it is the object of the invention to provide a valve mechanism wherein excessive heating of the parts will be prevented, and in which simple but efficient actuating means are provided for the valve mechanism.

Further objects of the invention will be understood from the following description of the accompanying drawings, in which;

Figure 1 is a longitudinal section through a cylinder and valve mechanism of an internal combustion engine constructed in accordance with the invention.

Fig. 2 is a longitudinal section on the line 2-2 of Fig. 1.

Fig. 3 is a side elevation, partly broken away, of an internal combustion engine showing the actuating mechanism for the improved valve structure.

Fig. 4 is a transverse section on the line 4-4 of Fig. 1.

In the drawings a working cylinder is shown at 1 surrounded by the water jacket 2. The working cylinder projects from a crank casing 3 through which extends the crank shaft 4. The working piston 3 is connected to connecting rod 6 which is mounted upon a crank throw 7 of shaft 4.

The valve mechanism includes a cylinder 8 having the water jacket 9 surrounding the same throughout a portion of its length and the radially spaced sleeve 10 surrounding the opposite end of the cylinder 8. The casing for the valve mechanism, as thus constructed, is mounted upon the top of the casing forming cylinder 1 and water jacket 2 with the valve casing extending transversely of cylinder 1. The valve casing is, preferably, supported at an inclination to the axis of cylinder 1 and is so arranged that the end

thereof having the water jacket 9 is in longitudinal alinement with the cylinder 1, while the portion of the valve cylinder having sleeve 10 projects laterally beyond the working cylinder. Water jacket 9 may connect with water jacket 2 with an inlet 11 provided in jacket 2, and an outlet 12 provided in jacket 9.

At the side of the cylinder 1 and valve cylinder 8 adjacent water jacket 9, a casing 13 is provided extending from crank casing 3 and overlying the end of cylinder 8. This casing contains the actuating mechanism for the valves, the end of cylinder 8 adjacent said actuating mechanism being open so as to readily receive operating connections from the actuating mechanism.

The actuating mechanism for the valves includes a shaft 14 journaled in the crank casing and rotated at one-half engine speed and in the direction of rotation of the crank shaft 4 by means of the train of gearing 15. Eccentrics 16 and 17 are fixed upon shaft 14 with the eccentric 17 one-fourth of a revolution in advance of eccentric 16. Rock arms 18-19 are connected to eccentric 16-17 through the lugs 20, and these rock arms extend upwardly through casing 13. Intermediate of their ends the rock arms are fulcrumed in rock bearings 21. The upper ends of the rock arms are in longitudinal alinement beyond the end of cylinder 8 and are provided with connecting links 22-23. These connecting links are secured to the piston valve and the sleeve valve of the valve mechanism respectively, as will be hereinafter described.

A piston valve is mounted in cylinder 8 and is, preferably, formed as a sleeve 25 having piston heads 26-27 at its respective ends forming an annular space 28 between said piston heads. The piston valve is mounted in cylinder 8 so that head 26 closes the end of cylinder 8 adjacent the actuating mechanism for the valve structure, and the head 27 reciprocates within the portion of cylinder 8 opposite the sleeve 10. The space 28 is thus in alinement with working cylinder 1 and communicates with the same by way of the port 30. A usual spark plug 31 is arranged in the space 28.

A sleeve 32 extends through sleeve 25 with a shoulder 33 upon said sleeve abutting against the end of sleeve 25 at the head 26, and nuts 34 threaded upon the opposite

end of sleeve 32 beyond the opposite end of sleeve 25 and abutting against the same. The sleeve 32 is connected by the arm 35 to the link 22 so that the movement of rock shaft 18 will reciprocate the piston valve within cylinder 8.

The sleeve valve of the valve mechanism is shown at 37 mounted in the annular space 38 between cylinder 8 and sleeve 10. The annular space 38 is open at its outer end as shown at 40, and the sleeve valve 37 is provided with an annular port 41 opening to space 38 at its outer end as shown at 42 and opening at its inner end through

15 the inner periphery of the sleeve valve as shown at 43. The inner end of the sleeve valve is cut away at the side thereof, as shown at 44, so as to form a passage leading to an inlet 45 extending through the wall 20 of sleeve 10 to the annular space 38.

The outer end of the sleeve valve is provided with a cap 46 extending over the outer open end 47 of the cylinder 8. A rod 48 extends through the sleeve 32, and the outer

25 end of the same is provided with a shoulder 51 abutting against cap 46 with a continuation of said rod extending through cap 46. Nuts 50 are threaded upon the outer end of said rod to detachably connect the sleeve 30 valve to rod 48. The inner end of rod 48 is connected by an arm 52 to the link 23 so that movement of rock arm 19 will actuate sleeve valve 37.

Ports 54 extend through cylinder 8 at 35 the annular space 38. The sleeve valve 37 is arranged to move outwardly beyond ports 54 so as to permit the latter to communicate with inlet 45 through the passage 44, and is arranged to be moved inwardly so as to 40 close ports 54 and subsequently open the same by way of openings 43. It will be understood that the outer end of ports 41 is open to the space 38 which, at its open end 40, forms a discharge. The piston valve 45 reciprocating within cylinder 8 is adapted to open and close ports 54 to the space 28 which is in communication with the working cylinder by way of port 30.

As shown in Fig. 1, when the working 50 piston is upon its dead center at the beginning of the expansion stroke, the piston valve is at its inner limit of movement closing ports 54, and the sleeve valve is midway of its movement and moving inwardly 55 with ports 54 closed by said sleeve valve.

At the beginning of the succeeding exhaust stroke, the sleeve valve will have moved to cause openings 43 to register with ports 54, and during said exhaust stroke ports 54 60 will be gradually cut off by the outward movement of the sleeve valve. The piston valve will still cover ports 54 as the exhaust stroke starts, but its continued outward movement will uncover said ports during 65 said stroke. As a result an exhaust pas-

sage is provided by way of port 30, space 28, ports 54, port 41, and space 38 to the discharge 40. The sleeve valve will have returned to the position shown in Fig. 1 as the suction stroke commences, and during 70 said stroke the outward movement of said valve will open inlet 45 to ports 54 by way of passage 44. At the same time ports 54, which have been uncovered by piston valve head 27, will be gradually cut off by the inward movement of said head. While the ports 54 remain open an inlet passage is provided through the same to space 28 and the port 30.

When the compression stroke starts, 80 ports 54 are closed by head 27 and the inward movement of said head will retain said ports closed during the stroke. At the same time the inward movement of the sleeve valve will also gradually shut off said ports. 85

When the cycle of operation is thus completed, the ports will again be in the position shown in Fig. 1 ready for a repetition of the engine action.

Various changes will be made without departing from the spirit of the invention 90 as claimed.

What is claimed is:

1. An internal combustion engine including a working cylinder, a valve chamber extending across the top of said cylinder and communicating with the same at one end, a sleeve surrounding said valve chamber at the other end thereof to form an annular space between the valve chamber and sleeve, 95 a water jacket surrounding the first mentioned end of said valve chamber, a port leading from said valve chamber to said annular space, a piston valve within said valve chamber, and a sleeve valve within said annular space, said valves functioning to control the inlet and exhaust through 100 said port.

2. An internal combustion engine including a working cylinder, a valve chamber extending across the top of said cylinder and communicating with the same, a sleeve surrounding said valve chamber to form an annular space, a port leading from said valve chamber to said annular space, a piston valve within 110 said valve chamber, having heads at opposite sides of the communication with said working cylinder and forming a passage between said heads, and a sleeve valve within 115 said annular space, said valves functioning to control the inlet and exhaust through said port.

3. An internal combustion engine including a working cylinder having a water jacket, a valve chamber extending across the top of said cylinder and communicating with the same, a sleeve surrounding said valve chamber to form an annular space, a partition in the latter forming a water jacket 125 communicating with the water jacket of 130

- said working cylinder and a space beyond said water jacket for the passage of fuel, a port leading from said valve chamber to said last mentioned space, a piston valve 5 within said valve chamber, and a sleeve valve within said last mentioned space, said valves functioning to control the inlet and exhaust through said port. 65
4. An internal combustion engine including a working cylinder, a valve chamber extending across the top of said cylinder and communicating with the same, a sleeve surrounding said valve chamber to form an annular space, a port leading from said 70 valve chamber to said annular space, a piston valve within said valve chamber controlling a passageway from the working cylinder to said port, and a sleeve valve within said annular space controlling fuel inlet and exhaust through said port and having an annular port communicating with said annular space at its outer end and opening at its inner end through the inner periphery of the sleeve valve. 75
- 15 5. An internal combustion engine including a working cylinder, a valve chamber extending across the top of said cylinder and communicating with the same, a sleeve surrounding said valve chamber to form an 80 annular space, a port leading from said valve chamber to said annular space, a piston valve within said valve chamber, a sleeve valve within said annular space, a driving connection for said piston valve, and a driving connection for said sleeve valve extending through said piston valve and connected to said sleeve valve at the outer end of said annular space. 85
- 20 6. An internal combustion engine including a working cylinder, a valve chamber extending across the top of said cylinder and communicating with the same, a sleeve surrounding said valve chamber to form an 90 annular space, a port leading from said valve chamber to said annular space, a piston valve within said valve chamber, a sleeve valve within said annular space, a driving connection for said piston valve, and a driving connection for said sleeve valve extending through said piston valve and connected to said sleeve valve at the outer end of said annular space, said valves being detachably secured to their driving connections. 95
- 25 7. An internal combustion engine including a working cylinder, a valve chamber extending across the top of said cylinder and communicating with the same, a sleeve surrounding said valve chamber to form an 100 annular space, a port leading from said valve chamber to said annular space, a piston valve within said valve chamber, a sleeve valve within said annular space, a driving connection for said piston valve, a driving connection for said sleeve valve extending through said piston valve and connected to said sleeve valve at the outer end of said annular space, said valves being detachably secured to their driving connections. 105
- 30 8. An internal combustion engine including a working cylinder, a valve chamber extending across the top of said cylinder and communicating with the same, a sleeve surrounding said valve chamber to form an 110 annular space, a port leading from said valve chamber to said annular space, a piston valve within said valve chamber, a sleeve valve within said annular space, a driving connection for said piston valve, a driving connection for said sleeve valve extending through said piston valve and connected to said sleeve valve at the outer end of said annular space, said valves being detachably secured to their driving connections, and means for removing said valves through the outer ends of said valve chamber and annular space. 115
- 35 9. An internal combustion engine including a working cylinder, a valve chamber extending across the top of said cylinder and communicating with the same, a sleeve surrounding said valve chamber to form an 120 annular space, a port leading from said valve chamber to said annular space, a piston valve within said valve chamber, a sleeve valve within said annular space, a driving connection for said piston valve, a driving connection for said sleeve valve extending through said piston valve and connected to said sleeve valve at the outer end of said annular space, said valves being detachably secured to their driving connections. EVERETT R. BURTNETT.
